PRESSURE COMPENSATED VALVE DEVICE
FOR WELL TOOLSBernard Kriegel, San Francisco, Calif., assignor
to Baker Oil Tools, Inc., Vernon, Calif., a corporation of California

Application July 7, 1947, Serial No. 759,321

12 Claims. (Cl. 166—11)

1

This invention relates to well tools, and more particularly to valve mechanisms forming part of such tools, especially employable in connection with the cementing, acidizing, washing, production, etc., of oil and gas wells.

Some forms of sub-surface well tools used in the cementing of a well bore embody a valve device which is subject to the pressure of the fluid in the tubing string connected to a well tool, of which the valve device forms a part. The fluid pressure differential within the tubing string and well tool over the external pressure tends to maintain the valve device in closed position, and renders it difficult to move the valve to open position when desired. As an example, a valve member which moves downwardly into seating engagement with a cooperable valve seat is subjected to a hydrostatic head of cement slurry within the tubing string tending to keep the valve member in closed position and precluding its movement to open position.

Some forms of well tools of the character indicated may be used in connection with the swabbing of the well bore. However, the valve device, and particularly a downwardly seating valve device, may be inadvertently shifted to open position upon the creation of a suction effect in the tubing string attached to the well tool or within the well tool itself, thereby preventing the desired swabbing effect from occurring.

Accordingly, it is an object of the present invention to provide a valve device in a well tool, in which the effects of pressure thereon tending to produce and maintain its closing are largely minimized.

Another object of the invention is to provide a well tool valve device adapted to be moved between open and closed position without restraint or interference by fluid pressure within the tool.

A further object of the invention is to provide a well tool in which the hydrostatic head of fluid, or fluent substances, such as cement slurry, within the tubing string coupled to the tool has substantially no effect upon the movement of a control valve member in said tool from closed position to open position.

Yet another object of the invention is to provide a well tool through which a suction or swabbing operation can be performed without hazard of pressure differentials inadvertently opening a control valve in said tool.

This invention has other objects that will become apparent from a consideration of the embodiments shown in the drawings accompanying and forming part of the present specification. These forms will now be described in detail, but

2

it is to be understood that such detailed description is not to be taken in a limited sense, since the scope of the invention is best defined by the claims appended hereto.

5 Referring to the drawings:

Fig. 1 is a longitudinal section through a well tool located in a well casing, with its valve device in open position.

Fig. 2 is a longitudinal section on an enlarged 10 scale through the valve device, whose parts are illustrated in open position.

Fig. 3 is a view similar to Fig. 2, with the valve device closed.

Fig. 4 is a side elevation of the lock device for 15 holding the valve mechanism in a predetermined position.

Fig. 5 is a view similar to Fig. 2 of a modified form of valve device.

The invention is disclosed in the drawings as 20 applied to a well packer of a type designed to force fluid under pressure through the perforations of a well casing. It is to be understood, however, that it has application to any type of well tool, through or from which fluid flow is to be controlled.

Specifically, the well tool consists of a body 10, 25 suitably secured as by threading to the lower end of a string of tubing or drill pipe 11, by means of which the tool is conveyed through the well casing 12 to the desired operating point therein. The body consists of an upper body member 13, 30 a lower body member 14, and an intermediate body member 15 connecting the upper and lower members together in spaced relation. The general type of well tool shown is a packer described and claimed in the application of Charles E. Costello, Serial No. 391,548, filed May 2, 1941, for "Well Devices," now Patent No. 2,466,305.

The upper and lower portions of the tool are 35 substantial duplicates, being connected to the intermediate body member 15 in opposed relation. A description of the upper portion should suffice for the lower portion as well.

The upper body member 13 includes an elongate mandrel or nipple 16 having a sub 17 40 screwed on its upper end, and a lower ported sub 18 secured to its lower end. One or more packing cups 60, 61 of rubber or similar material are 45 suitably secured on the mandrel, with the lower cup 60 facing downwardly and the upper cup 61 facing upwardly. These packing cups are 50 adapted for slidable sealing engagement with the wall of the well casing 12 to prevent both upward and downward flow of fluid between the 55 upper body member 13 and the casing wall.

An upper by-pass tube 20 is positioned within the upper body member to provide an annular space 21 therewith. Its upper member is threaded into a by-pass T 22, which is suitably secured, as by welding, to the upper by-pass sub 17, through which it opens outwardly into the tubing-casing annulus 23 above the upper packing 61. The lower end of the by-pass tube 20 extends through an inner flange 24 on the lower sub 18, containing a rod packing 25 pressed in leakproof engagement against the exterior of the tube by a suitable packing nut 26, to prevent downward flow of fluid through the annulus 21 beyond the flange 24.

As stated above, the construction of the lower tool portion is substantially the same as the upper, with the parts facing in the opposite direction, so that fluid passage between the lower body member 14 and casing wall in both upward and downward directions is prevented, and upward flow of fluid through the lower annulus 21a beyond the flange 24a is prevented by the flange 24a, packing 25a and packing nut 26a surrounding the lower by-pass tube 20a. For convenience in designation, the lower parts are numbered the same as the corresponding upper parts with the suffix "a" added.

The upper and lower tool portions are held together in spaced relation by the intermediate body member 15, which actually forms part of the by-pass of the tool. This intermediate body member is secured to the upper and lower subs 18, 18a and may be made of any length desired, depending upon the spacing required between the upper and lower packing cups 60, 60a. The by-pass around the packings extends from a point outside the tool below the lowermost packing 61a to a point outside the tool above the uppermost packing 61. More specifically, this by-pass passage is constituted by the lower T 22a, lower by-pass tube 20a, intermediate body member 15, upper by-pass tube 20, and upper by-pass T 22.

The upper sub 18 is provided with one or more upper outlets or ports 27 adjacent the packing cup 60 and flange 24, and the lower sub 18a is similarly provided with one or more lower outlets or ports 27a adjacent the lower packing cup 60a and flange 24a. Fluid cannot pass directly from the upper body annulus 21 to the lower body annulus 21a because of the flanges and packings around the by-pass tubes, but must pursue an indirect course. The fluid may be pumped downwardly through the tubing 11 into the upper body member annulus 21, exiting through the upper ports 27 into the localized annular zone 28 defined by the upper and lower packings 60, 60a and by the intermediate body member 15 and casing 12. This fluid may flow downwardly through the zone and enter the lower body member 14 through the lower ports 27a, where the fluid can pass downwardly through the annulus 21a around the lower by-pass tube 20a into a valve body or housing 29 screwed into the lower end of the lower sub 17a. The fluid may then pass through the valve outlets or ports 30 in the housing to the exterior of the tool 23a below the lower packing cup 61a, from where it may flow upwardly into the lower by-pass T 22a, through the lower by-pass tube 20a, intermediate by-pass member 15, tube 20, and upper by-pass T 22, into the tubing-casing annulus 23 above the upper packing cup 61.

The allowing of the fluid to pursue the course just described is dependent upon the control of

the fluid flow through the valve ports 30 at the lower end of the tool. Such control is obtained through a valve mechanism, including a valve stem 31 within the housing to which a valve member 32 is secured. The valve stem has a rod extension 33 depending through a lock sleeve 34 threaded into the lower end of the housing 29. The lower end of the rod extension is attached to a drag device, which, in the present instance, consists of a lower collar 35 and guide 36 threaded on the rod with a plurality of outwardly bowed drag springs 37 secured to the lower collar and extending upwardly for attachment to an upper collar 38 slidably mounted on the rod 33.

The drag device resists movement of the rod extension 33, valve stem or rod 31 and valve member 32 in both longitudinal directions within the casing 12. That is, downward movement of the tubing string 11 and attached body 10 of the tool tends to move the valve body or housing 29 downwardly with respect to the valve member 32, causing the latter to move relatively in an upward direction which, in the specific design disclosed in the drawings, is its open position. Similarly, elevating of the tubing string 11, body 10 and valve housing 29 tends to cause the valve member to move relatively in a downward direction, or to closed position.

The positions of the valve member 32 in the valve housing 29 and with respect to the valve ports 30 are determined positively by a lock device. In the present instance, this device includes a lock pin 39 secured to the rod extension 33 and extending into a lock slot 40, 41 formed in the sleeve 34. This slot has an upper lateral or transverse portion 40, which will receive the pin 39 and hold the valve member in an upper open position, and with a longitudinal portion 41 which will permit the lock pin to move lengthwise of the sleeve 34 and allow the valve member 32 to move to closed position, as more specifically described hereinafter.

The valve member includes an elongate body 42, whose lower end is threaded onto the rod 31. This body carries a packing ring or sleeve 43 on its upper portion, which is confined between a lower ring 44, welded to the body, and an upper head 45 threaded on the upper end of the body. The packing member 43 is adapted to be drawn relatively downwardly through a downwardly and inwardly tapered guiding face 46 in the housing 29 into a cylindrical seating surface 47, disposed in the valve housing above the port 30, such movement being permitted when the lock pin 39 is in alignment with the longitudinal lock slot 41 in the sleeve 34. The housing is formed as a cylinder 48 below the ports 30, along whose wall 48a a lower annular piston 49, integral with the body 42, may slide, leakage between the annular piston 49 and cylinder wall 48a being prevented by suitable piston rings 50 of rubber, or other appropriate material, in peripheral piston ring grooves 51.

The valve body 42 is generally tubular in form, having a passage 52 therethrough which can communicate with the annular space 53 between the piston rod 31 and cylinder wall 48a below the annular piston 49 through ports 54 formed through the body below the annular piston. In order to prevent fluid from moving downwardly out of the cylinder space 53, rod packing rings 55 are provided in grooves 56 in the upper portion 57 of the lock sleeve 34, such packings being in slidable sealing engagement with the rod.

Moreover, a thread seal 58 may be provided between the upper end of the sleeve 34 and the cylinder 48 to prevent leakage of fluids through their threaded interconnection. In effect, the upper end 57 of the lock sleeve forms a cylinder head, beyond which fluids cannot pass.

The inside diameter of the cylindrical seating surface 47 is substantially less than the inside diameter of the cylinder 48, with which the annular piston 49 is in slideable engagement. These diameters are chosen so that the effective area A across the valve member, when its seal ring or sleeve 43 is disposed within the cylindrical seating surface 47, is substantially equal to the annular area B of the cylinder space 53 between the inner wall 48a of the cylinder and the rod 31.

When the valve is in closed position, as illustrated in Fig. 3, fluid under pressure within the tool above the valve member 32 acts downwardly across the effective area A and tends to hold the valve member in such downward closed position. Such fluid pressure is also transmitted through the fluid in the passageway 52, 54 into the annular cylinder space 53, acting upwardly on the piston 49 and lower end of the body 42 across the annular area B. Accordingly, it is seen that, since the areas A and B are equal to one another, the fluid pressure force acting in a downward direction and tending to hold the valve closed is equal to the fluid pressure force acting in an upward direction and tending to move the valve member 32 upwardly, to shift its packing 43 out of the cylindrical seating surface 47, or to open position. Thus, the valve member may be moved between open and closed positions with facility simply by appropriate manipulation of the tubular string 11, the drag springs 37 engaging the wall of the well casing 12 with sufficient force to tend to hold the valve member 32 stationary and allow the valve housing 29 and remainder of the well tool to be shifted longitudinally thereof.

One representative use of the valve mechanism in question is in connection with the cementing of a casing. The tool disclosed in Fig. 1 is lowered through the well casing 12 until the inner packing cups 60, 60a are disposed on opposite sides of casing perforations 59, through which cement slurry, or other cementitious material, is to be ejected. During this running-in operation, the drag springs 37 resist lowering of the valve member 32 within the casing, and, accordingly, the valve member 32 occupies an upper position with respect to the cylindrical seating surface 47, with the packing sleeve 43 disposed thereabove and within a portion of the housing 29 having a much larger internal diameter than the external diameter of the packing 43, providing an annular space through which fluid entering the ports 30 may flow upwardly through the tool, as well as in a reverse direction (see Figs. 1 and 2).

Circulating fluids may be pumped down the tubing string 11 with the valve in open position, as illustrated in Figs. 1 and 2, passing through the upper annulus 21 and out through the upper ports 27 into a localized zone 28 between the packing members 60, 60a; thence into the lower ports 27a and lower annular passage 21a, and around the valve packing 43, through the cylindrical seating surface 47, and the ports 30 to a point below the lowermost packing member 61a. The fluid then may proceed upwardly through the by-pass passage 22a, 20a, 15, 20, 22 discharging into the tubing-casing annulus 23 above the upper packing member 61 for continued upward movement through such annulus to the top of the well bore.

A charge of cement slurry may be started down the tubing string 11 and when its lower end is near the well tool, the tubing string may be elevated several inches, say two or three inches, to move the cylindrical seating surface 47 up over the packing sleeve 43, thus closing the valve and the ports 30 to passage of fluids between the interior of the well tool and the exterior of the well tool below the lowermost packing 61a. Such relative movement between the valve member 32 and its cooperable cylindrical seating surface 47 can occur, since the lock pin 39 is disposed within the longitudinal portion 41 of the J-lock slot.

The cement slurry passes from the lower end 15 of the tubular string 11, through the upper annulus 21 in the body and out through the upper ports 27, being forced under pressure through the casing perforations 59 for deposition behind the well casing 12. Such cement slurry cannot 20 flow through the lower ports 27a into the lower body member 14, since the valve is in closed position and the fluid in the lower portions of the body member 14 is prevented from passing downwardly and out through the ports 30.

Following the deposition of the required amount of cement slurry through the perforations 59, any excess may be flushed from the tool by 25 lowering the tubular string 11, and the tool body 10 and valve housing 29 attached thereto, several inches to dispose the horizontal portion 40 of the lock slot opposite the pin 39, whereupon the tubular string 11 may be turned slightly to the left to cause the lock pin to be located in the upper locking portion 40 of the slot, wherein the valve 30 packing 43 is held elevated above the seating surface 47, or in open position. Washing fluid may 35 then be pumped down the tubular string, forcing the cement slurry ahead of it, and causing it to flow through the upper annulus 21, upper port 27, into the localized zone 28, then through the lower port 27a and lower annulus 21a and around the valve packing 43, to discharge through the valve ports 30, whereupon the excess cement slurry, followed by the washing fluid, may flow through the by-pass passage 22a, 20a, 15, 20, 22 into the 40 annulus 23 above the upper packing 61 for passage to the top of the well bore and appropriate disposal.

The cement slurry may also be disposed of by 45 circulating the washing fluid in a direction reverse to that described, by initially pumping it down through the tubing-casing annulus 23, the washing fluid passing through the by-pass passage and the ports 30 for upward flowing around the valve member 32, body passages 21a, 21 and ports 27a, 27 into the tubing string 11, carrying the excess cement slurry in the tubing string 50 ahead of it to the top of the well bore.

In the event that the excess cement slurry is to 55 be disposed of by pumping the washing fluid down the tubular string, conditions sometimes render it difficult to relatively move the valve member 32, or equivalent valve, to open position. For example, in the event that there is an extended column of excess cement slurry present in the tubing string of, say, 1,000 feet, the hydrostatic head of such cement slurry acting downwardly on the valve member exerts a downward closing force thereon, which may be substantially greater than the force of friction of the drag springs 37 60 against the wall of the well casing 12. Downward movement of the tubing string 11 and attached body 10 and valve housing 29 cannot, therefore, result in opening of the valve. By virtue of a present invention, the pressure differential with- 65 70 75 in a tubing string 11, occasioned by the presence

of the high head of cement slurry, does not impose a resultant downward closing force on the valve member 32.

The pressure acting downwardly on the valve member 32 over the area A is exactly equal to the same pressure acting upwardly on the valve member over the annular area B, such forces being equal and opposite. In other words, the pressure within the tubing string 11 and within the tool imposes no restraints on the free movement of the valve member 32 within the valve housing 29 between open and closed positions. Accordingly, with a high head of cement slurry within the tubing string 11, the latter need merely be lowered several inches to effect relative elevation of the packing member 43 from the cylindrical seating surface 41, which opens the ports 30 and allows excess cement slurry to be pumped downwardly and out of the tubular string, in the manner described above.

It is to be understood that the areas A and B need not be made exactly equal to each other. As an alternative, the area A may be made slightly greater than the area B, so as to have a resultant force in a downward direction, tending to keep the valve closed in response to pressure in the tubular string 11 and to a body 10. However, it is preferred that the overbalancing hydraulic force in a downward direction on the valve member 32 be less than the frictional force of the drag springs 37 against the wall of the casing 12, to permit the valve to be opened readily whenever desired. On the other hand, the area B may be made greater than the annular area A, in order to cause the fluid pressure within the tubular string 11 and tool body 10 to assist in opening of the valve. But, here again, the overbalancing of hydraulic force in an upward direction preferably should not be greater than the frictional force of the drag springs 37 against the wall of the casing, in order to prevent the internal fluid pressure from inadvertently opening the valve.

Another specific use of the tool described in Fig. 1 is in connection with the swabbing of the well through casing perforations. Upon the creation of a suction effect in the tubular string relative to the pressure externally thereof, such as through lowering of the fluid level in the tubular string 11, the outer packing members 61, 61a effectively seal the annular zone 28 therebetween, and prevent fluid in the annuli 23, 23a both above and below the packing cups 61, 61a from passing into the localized zone 28. During such swabbing operation, it is desired that the valve be closed and that such suction effect be incapable of opening the valve, such as might occur if the pressure in the lower annular zone 23a around the tool were greater than the pressure within the tubing string 11 and tool body 10.

The arrangement disclosed insures that the valve will remain in closed position. The greater pressure externally of the valve housing acts through the ports 30 in two different longitudinal directions on the valve member 32. First, it acts in a downward direction on the piston 49 over the annular area C between the exterior of the valve body 42 and the wall 48a of the cylinder above the annular piston 49, and it acts in an upward direction over a smaller annular area D between the exterior of the body 42 and the inside surface 47 of the cylindrical seat. In addition, the external pressure acts upwardly over the area E of the rod 31. Since the annular area C is essentially equal to the sum of the annular area D and rod area E, the pressure externally of the tool has very little, if any, capacity for shifting the valve

member 32 in either direction during the swabbing operation, and the valve remains in the closed position illustrated in Fig. 3. Accordingly the swabbing operation can take place, without fear of hydraulic forces inadvertently opening the valve and permitting fluid to flow upwardly therethrough.

A somewhat modified form of valve is disclosed in Fig. 5, which is essentially the same as in the other embodiment of the invention. Instead of a piston type of valve being disclosed as in Figs. 1, 2 and 3, a poppet type of valve member 32a is illustrated. The valve housing 29, annular piston 49 and cylinder 48 arrangement is essentially the same as in the other modification. The only difference resides in the provision of a downward and inwardly tapering seat 62 in the valve housing 29 above the ports 30, which is adapted to be engaged by a valve head 63 threaded on the upper end of an elongated tubular body 42a. In order to insure against leakage when the head 63 engages the seat 62, an intervening seal ring 64 may be disposed in the latter.

When the valve member 32a is in open position, its head 63 is disposed above the seat 62 and fluids may flow around the head, and between the interior of the tool body 10 and the ports 30. When the valve head 63 is in its lower position and engaged with the seat 62 and seal ring 64, the ports 30 are closed and cannot be opened inadvertently by fluid pressure.

The pressure actuatable area F acting downwardly on the valve head 63 is the area across the outermost contact circle between the head and the seal ring 64. The effective area on the valve member 32a in an upward direction is the annular area G between the rod 31 and the cylinder wall 48a, as indicated above in connection with the other embodiment of the invention. This latter annular area is made equal to the other area F, in order that fluid pressure may act on the valve device with equal force both downwardly and upwardly, and thus not tend to shift the valve device in one direction or the other. Of course, as described in connection with the other embodiment, the relationship between the areas can be varied to obtain an overbalanced hydraulic force in one direction or the other, depending upon the effects desired.

For the purpose of preventing cement or other ingredients from plugging the passage 52 through the valve member body 42, such passage may be provided with a barrier plug 65 slidably mounted therein and carrying a suitable seal ring 66 in a ring groove 61, for preventing fluid leakage in both directions between the plug and the wall of the body. Upward movement of the plug 65 within the body is prevented by its engagement with an internal flange 68 on the head member 45 while its downward movement is governed by a liquid 69, such as light oil, completely filling the annular cylinder space 53 below the piston 49 and also the passage 42 in the body below the plug 65. This oil may be introduced into the passage and cylinder space through a central hole 70 in the barrier plug, which is then closed by a suitable pipe plug 71.

The barrier plug 65 is floating, or is slidable, within the valve member body 42, transmitting the pressure on its upper surface to the oil 69 in the passage 42 and cylinder space 53. It is thus seen that the same unit pressure on the barrier plug 65 is imposed upon the oil 69, which is effective for operation upon the annular piston 49 and lower end of the body 42 in the same manner as

if the liquid in the well tool were present within the passage 52 and cylinder space 53 in the absence of the barrier plug.

It is apparent that the plug 65 prevents the passage 52 from becoming filled with cement particles or other undesired elements, precluding plugging of the passage and insuring transmission of the fluid pressure to the underside of the annular piston 49 and valve member body 42.

Although the valve device has been described with particular reference to a tool designed for forcing fluid through casing perforations, it is apparent that it may be applied to other specific tools as well. It is also clear that it may be used in the performance of acidizing, testing, washing, production and other well bore operations, in addition to the cementing and swabbing operations specifically referred to.

It is, accordingly, apparent that a valve device for a well tool has been disclosed, which is not subject to the pressure conditions within the tool tending to move it from its desired position within the valve housing. The valve is only moved purposely when required through manipulation of the tubing string to which the well tool is attached.

Having thus described my invention, what I claim and desire to secure by Letters Patent is:

1. A well tool, including tubular means having instrumentalities for attachment to a tubular string to enable the well tool to be lowered in a well bore, said tubular means having an inlet and an outlet, a valve seat in said tubular means between said inlet and outlet, a valve member movable longitudinally within said tubular means to and from engagement with said seat to determine the flow of fluid through said outlet, said valve member having a first fluid pressure actuatable surface facing in one longitudinal direction and subject to the pressure of fluid within said tubular means to tend to hold said valve member engaged with said seat, said valve member having a second fluid pressure actuatable surface disposed on the opposite side of said outlet from said seat and subject to fluid pressure to tend to move said valve member from said seat, said valve member having a passage establishing fluid pressure intercommunication between said surfaces when said valve member is in engagement with said seat and communicating with said inlet and tubular string when said valve member is in engagement with said seat, means for preventing the fluid pressure on the outlet side of said seat from acting on said second fluid pressure actuatable surface when said valve member is in engagement with said seat, and means connected to said valve member for effecting its movement to and from engagement with said seat.

2. A well tool, including a valve housing embodying instrumentalities for attachment to a tubular string to enable the well tool to be lowered in a well bore, said housing having an inlet, an outlet and a seat between said inlet and outlet, valve means in said housing engageable with said seat to prevent flow of fluid therethrough between said inlet and outlet, said valve means having a first fluid pressure actuatable surface facing in one longitudinal direction and subject to pressure of fluid within said housing to tend to shift said valve means downstream of said housing into engagement with said seat, said valve means having a piston slidably engaged with said housing to one side of said seat, said

piston having a second fluid pressure actuatable surface facing in the opposite longitudinal direction to said first surface, said valve means having a passage establishing fluid pressure intercommunication between said surfaces when said valve means engages said seat and communicating with said inlet and tubular string when said valve means engages said seat, said surfaces being of substantially equal areas in order that the fluid pressure acting on said first surface is substantially counterbalanced by the fluid pressure acting on said second surface, means for preventing fluid pressure on the outlet side of said seat from entering said housing for action upon said second fluid pressure actuatable surface when said valve means engages said seat, and means for effecting movement of said valve means from said seat.

3. A well tool, including a valve housing embodying instrumentalities for attachment to a tubular string to enable the well tool to be lowered in a well bore, said housing having an inlet, a seat and an outlet through said housing disposed longitudinally to one side of said seat, a member in said housing engageable with said seat to prevent flow of fluid between said member and seat, a rod connected to said member and extending through said housing in leakproof relation with respect thereto, said member having an annular piston which is slidably engageable with the inner wall of said housing on the opposite side of said outlet from said seat and providing with said rod an annular cylinder space that is out of communication with fluid under pressure on the outlet side of said seat when said member engages said seat, said member having a fluid pressure actuatable surface subject to fluid pressure in said housing when said member engages said seat, which surface is substantially equal in area to the transverse area of said annular piston in said annular cylinder space, said member having a passage establishing fluid pressure intercommunication between said surface and piston when said member engages said seat and communicating with said inlet and tubular string when said member engages said seat, and means connected to said rod for effecting movement of said member to and from said seat.

4. A well tool, including a valve housing embodying instrumentalities for attachment to a tubular string to enable the well tool to be lowered in a well bore, said housing having an inlet, a seat and an outlet disposed below said seat, a member in said housing movable downwardly into engagement with said seat, a rod connected to said member and extending downwardly through said housing in leakproof relation with respect thereto, said member having an annular piston which is slidably engageable with the inner wall of said housing below said outlet and providing with said rod an annular cylinder space that is out of communication with fluid under pressure on the outlet side of said seat when said member engages said seat, said member having a passage establishing fluid pressure intercommunication between an upwardly facing fluid pressure actuatable surface on said member and said cylinder space below said piston when said member is in engagement with said seat, said passage communicating with said inlet and tubular string when said member is in engagement with said seat, and means connected to said rod for effecting movement of said member to and from said seat.

5. A well packer, including a hollow body

adapted to be connected to a tubular string for lowering in a well casing; said body having packing means thereon for effecting a seal with the wall of said casing; valve means for controlling fluid flow in said body, comprising a valve housing secured to said body and having an inlet, a seat and an outlet disposed below said seat, a member in said housing movable downwardly into engagement with said seat, a rod connected to said member and extending downwardly through said housing in leakproof relation with respect thereto, said member having an annular piston which is slidably engageable with the inner wall of said housing below said outlet and providing with said rod an annular cylinder space that is out of communication with the fluid under pressure on the outlet side of said seat when said member engages said seat, said member having a passage establishing fluid pressure communication with an upwardly facing fluid pressure actuatable surface on said member and said cylinder space below said piston when said member engages said seat, said passage communicating with said inlet and tubular string when said member is in engagement with said seat; and means connected to said rod and engageable with said casing for resisting movement of said member upon movement of said body and housing.

6. A well packer, including a hollow body adapted to be connected to a tubular string for lowering in a well casing, said body having packing means thereon for effecting a seal with the wall of said casing, a valve housing secured to the lower end of said body and having an inlet and an outlet and a valve seat between said inlet and outlet, a valve member engageable with said seat, said valve member having oppositely facing pressure actuatable surfaces of substantially equal areas, one of said surfaces communicating with said inlet and hollow body when said valve member engages said seat, means for preventing the fluid pressure on the outlet side of said seat from acting on said other surface when said valve member engages said seat, said valve member having a passage therein communicating with said inlet and hollow body and establishing fluid pressure intercommunication between said surfaces, in order that fluid under pressure within said housing can act simultaneously upon said oppositely facing surfaces when said valve member engages said seat; and means for effecting movement of said valve member to and from said seat.

7. A well packer, including a hollow body adapted to be connected to a tubular string for lowering in a well casing, said body having longitudinally spaced packing means thereon for effecting a seal with the wall of said casing, ports in said body establishing communication between the interior of said body and its exterior between said packing means, valve means for controlling flow of fluid in said body through said ports, comprising a valve housing secured to said body and having an inlet and an outlet and a valve seat between said inlet and outlet, a valve member engageable with said seat, said valve member having oppositely facing fluid pressure actuatable surfaces of substantially equal areas, one of said surfaces communicating with said inlet and hollow body when said valve member engages said seat, means for preventing the fluid pressure on the outlet side of said seat from acting on said other surface when said valve member engages said seat, said valve member having

5 a passage therein communicating with said inlet and hollow body and establishing fluid pressure intercommunication between said surfaces in order that fluid under pressure within said body and housing can act simultaneously upon said oppositely facing surfaces when said valve member engages said seat, and means for effecting movement of said valve member to and from said seat.

10 8. A well packer, including a hollow body adapted to be connected to a tubular string for lowering in a well casing, said body having longitudinally spaced packing means thereon for effecting a seal with the wall of said casing, ports in said body establishing communication between the interior of said body and its exterior between said packing means, valve means for controlling flow of fluid in said body and through said port, comprising a valve housing secured to said body and having an inlet, a seat and an outlet disposed below said seat, a member in said housing movable downwardly into engagement with said seat, a rod connected to said member and extending downwardly through said housing in leakproof relation with respect thereto, said member having an annular piston which is slidably engageable with the inner wall of said housing below said outlet and providing with said rod an annular cylinder space that is out of communication with fluid under pressure on the outlet side of said seat when said member engages said seat, said member having a passage establishing fluid pressure communication between an upwardly facing fluid pressure actuatable surface on said member and said cylinder space when said member engages said seat, said passage communicating with said inlet and tubular string when said member is in engagement with said seat, and means connected to said rod and engageable with said casing for resisting movement of said member upon movement of said body and housing.

35 9. A well tool, including tubular means adapted to be lowered in a well bore and having an inlet and an outlet, a valve seat in said tubular means between said inlet and outlet, a valve member movable longitudinally to and from engagement with said seat to determine flow of fluid therethrough, said valve member having oppositely facing transverse fluid pressure actuatable surfaces, one of said surfaces communicating with said inlet when said valve member engages said seat, means for preventing the fluid pressure on the outlet side of said seat from acting on said other surface when said valve member engages said seat, said valve member having a passage therein communicating with said inlet and establishing fluid pressure intercommunication between said surfaces in order that fluid under pressure within said tubular means can act simultaneously upon said oppositely facing surfaces when said valve member engages said seat, means for effecting movement of said valve member to and from said seat, and a movable barrier across said passage for transmitting the pressure of the fluid externally of the passage to fluid internally of the passage.

45 10. A well tool, including tubular means adapted to be lowered in a well bore on a tubular string and having an inlet and an outlet, a valve seat in said tubular means between said inlet and outlet, a valve member movable longitudinally to and from engagement with said seat, said valve member having a first fluid pressure actuatable surface facing in one longitudinal direction and subject to the pressure of fluid in the

inlet within said tubular means and tubular string above said valve member to tend to hold said valve member engaged with said seat, said valve member having a second fluid pressure actuatable surface facing in the opposite longitudinal direction and subject to fluid pressure to tend to move said valve member from said seat, said valve member having a passage establishing fluid pressure intercommunication between said surfaces when said valve member is in engagement with said seat and communicating with said inlet and tubular string when said valve member is in engagement with said seat, means for preventing the fluid pressure on the outlet side of said seat from acting on said second fluid pressure actuatable surface when said valve member is in engagement with said seat, means connected to said valve member for effecting its movement to and from engagement with said seat, and means disposed across said passage to prevent substantial entry of undesired substances thereinto.

11. A well tool, including tubular means having instrumentalities for attachment to a tubular string to enable the well tool to be lowered in a well bore, said tubular means having an inlet and an outlet, a valve seat in said tubular means between said inlet and outlet, a valve member engageable with said seat, said valve member having a transverse surface facing upstream and subject to the fluid pressure in said tubular means on the upstream side of said valve member to urge said valve member toward engagement with said seat, said valve member having a surface facing downstream, said valve member having a passage therein establishing fluid pressure intercommunication between said surfaces in order that fluid under pressure within said tubular means upstream of said valve member can act simultaneously upon said oppositely facing surfaces when said valve member engages said seat, said passage communicating with said inlet and tubular string when said valve member is in engagement with said seat, means for preventing the fluid pressure on the outlet side of

45

said seat from acting on said surface facing downstream when said valve member is in engagement with said seat, and means for effecting movement of said valve member to and from engagement with said seat.

12. A well tool, including tubular means adapted to be lowered in a well bore and having an inlet and an outlet, a valve seat in said tubular means between said inlet and outlet, a valve member movable longitudinally to and from engagement with said seat to determine flow of fluid therethrough, said valve member having oppositely facing transverse fluid pressure actuatable surfaces of substantially equal areas, one of said surfaces communicating with said inlet and tubular means when said valve member engages said seat, means for preventing the fluid pressure on the outlet side of said seat from acting on said other surface when said valve member engages said seat, said valve member having a passage therein communicating with said inlet and tubular means and establishing fluid pressure intercommunication between said surfaces in order that fluid under pressure within said tubular means can act simultaneously upon said oppositely facing surfaces when said valve member engages said seat, means for effecting movement of said valve member to and from said seat, and a barrier slideable in said passage to transmit the pressure of the fluid on one side of the barrier to the fluid on the other side of said barrier within the passage.

BERNARD KRIEGEL.
